[57] CLAIM

The ornamental design for a vehicle wiring harness connector, as shown and described.

DESCRIPTION

FIG. 1 is a bottom plan view of a vehicle wiring harness connector, showing our new design;

FIG. 2 is a top plan view thereof;

FIG. 3 is a front elevational view thereof;

FIG. 4 is a rear elevational view thereof;

FIG. 5 is a right side elevational view thereof; and

FIG. 6 is a left side elevational view thereof.

The electric cords in FIGS. 1-6 are shown broken away to depict indeterminate length.

FIG. 4

FIG. 5

FIG. 6
